[57] CLAIM

The ornamental design for a centrifuge, as shown and described.

DESCRIPTION

FIG. 1 is a perspective view of one embodiment of a centrifuge showing my new design, depicting the front, top and one side thereof;

FIG. 2 is an elevation view, showing the front of the centrifuge;

FIG. 3 is an elevation view, showing the rear of the centrifuge;

FIG. 4 is an elevation view, showing the left side of the centrifuge;

FIG. 5 is an elevation view showing the right side of the centrifuge;

FIG. 6 is a top plan view of the centrifuge;

FIG. 7 is a bottom plan view of the centrifuge;

FIG. 8 is a perspective view of another embodiment of a centrifuge showing my new design, depicting the front, top and one side thereof;

FIG. 9 is an elevation view, showing the front of the centrifuge of FIG. 8;

FIG. 10 is an elevation view, showing the rear of the centrifuge of FIG. 8;

FIG. 11 is an elevation view, showing the left side of the centrifuge of FIG. 8;

FIG. 12 is an elevation view, showing the right side of the centrifuge of FIG. 8;

FIG. 13 is a top plan view of the centrifuge of FIG. 8; and, FIG. 14 is a bottom plan view of the centrifuge of FIG. 8.
